UNITED STATES PATENT OFFICE.

GEORGE M. HYNDES, OF DALLAS, TEXAS.

AUTOMATIC BALL-BEARING SIDE BEARING FOR RAILROAD TRUCKS.

Application filed June 27, 1922. Serial No. 571,205.

To all whom it may concern:

Be it known that I, GEORGE M. HYNDES, a citizen of the United States, and a resident of Dallas, in the county of Dallas and State of Texas, have invented a new and Improved Automatic Ball-Bearing Side Bearing for Railroad Trucks, of which the following is a full, clear, and exact description.

This invention relates to automatic ball bearing side bearings for railroad trucks, and has for an object the provision of means associated with a side bearing whereby the shock of the weight of cars on the roadbed and rail joints is efficiently reduced so that the necessity for repairing the bed and the joints is greatly reduced. This invention has the relation of an improvement on my United States Patent No. 1,429,737, issued September 29, 1922, entitled "Automatic ball bearing side bearings for railroad trucks."

Another object resides in the particular construction and arrangement of parts which are hereinafter described and claimed and shown in the accompanying drawings.

The invention is illustrated in the drawings, of which—

Figure 1 is a vertical section taken on the line 1—1 of Fig. 2, which is a plan view.

Fig. 3 is a transverse vertical section taken on the line 3—3 of Fig. 2.

The form of the invention shown in the drawings is a preferred form, although it is understood that modifications in the construction and arrangement of the parts and in the character of the materials used may be adopted without departing from the spirit of the invention.

The invention as shown in the drawings relates to a side bearing device for railroad trucks and includes a side bearing plate 1 disposed on the underside of a car body 2 and over a truck bolster 3. The bearing plate 1 is adapted to rest or bear on a ball bearing 4 which is disposed for movement within a shallow receptacle or casing 5. The ball is held normally in the central position, as shown in Fig. 2 and described in the above-mentioned application, by means of

abutment plates 6 and 7 pressed forwardly 50 by springs 8 and 9.

The operation and relation of the bearing plates 1, the ball 4 and the casing 5 are clearly described in the above-mentioned application. My invention comprises the disposition beneath the casing 5 of a plurality of cushioning springs 10, 11, 12 and 13, as shown in Fig. 1. There may be any number of these springs disposed beneath the casing but their importance in connection with the casing 5 is that they permit a proper bearing relation between the casing 5, the ball 4 and the plate 1 and yet cushion the shock of the weight of the car transmitted through the plate 1 to the bolster frame 3. The springs above mentioned are suitably disposed within a casing 14 which at the ends has slots 15 and 16 formed therein to permit the rear ends of the abutment plates 6 and 7 to project out of the casing 5, as well as the stems 17 and 18, shown in Fig. 1 particularly. The interior dimensions of the casing or receptacle 14 are only slightly larger than the exterior dimensions of the casing 5, so that the casing 5 has very little lateral or longitudinal play within the receptacle 14 but has a proper amount of vertical movement due to the action of the springs. The end walls 19 and 20 of the receptacle 14 also prevent longitudinal movement of the casing 5 therewithin. The casing 5 is provided with a plurality of ears such as 21 which extend into lateral slots 22 formed in the side walls of the receptacle 14, and these ears are adapted to receive bolts 23 on the lower ends of which nuts 24 are placed to limit the upward movement of the casing 5 within the receptacle or casing 14.

Therefore, whenever the cars are moving over joints, the blow of the weight of the car instead of being directly transmitted thereto with full force is cushioned by reason of the interposition between the side bearing casing and the truck bolster of one or more springs or cushioning means to take up this blow. In this manner, therefore, the wear and tear on the roadbed and the rail

joints are eliminated to a considerable degree, and this result, in combination with the use of the particular side bearings shown, makes a very effective side bearing unit.

What I claim is:

A side bearing unit for railroad trucks which includes a truck frame, a receptacle on said frame, a bearing casing disposed within said receptacle, a plurality of springs

disposed beneath the casing and within the receptacle to cushion the downward movement of the casing under the weight of the car, and a single ball bearing within said casing, the interior of the casing being considerably larger than the ball bearing to permit a substantial freedom of movement of the ball bearing in all directions therewithin under the weight of the car.

GEORGE M. HYNDES.
